FEED COLLECTOR

Roy Lindquist, Baldwin, Wis.

Application March 7, 1942, Serial No. 433,781

3 Claims. (Cl. 119—61)

This invention relates to feed troughs, and particularly to feed troughs of the character employed for feeding poultry or the like, although it would be of utility in conserving food, regardless of the nature of its use.

It is an object of this invention to provide a trough for containing food and to associate it with a hollow base, to which food escaping from the trough would be directed, collected and reclaimed so that it may be restored or returned to the trough.

It is a further object of the invention to provide a hollow base with a suitable mounting or support for a trough and the provision of deflecting plates suspended from the edges of the trough, which deflecting plates extend downwardly into an opening in the hollow base, which hollow base may contain a drawer slideable therein which, upon removal from the hollow base, may be manipulated to return its contents to the trough.

It is an object of this invention furthermore to provide novel means by which the plates are suspended from the edges of the trough and preferably the said plates converge toward their lower edges, although the said edges are not in contact and the space between them permits the escape of the food into the hollow base.

It is a still further object of this invention to provide a feeding trough and collector for food escaping therefrom which possesses advantages in points of efficiency and which is comparatively inexpensive to produce and maintain.

With the foregoing and other objects in view, the invention consists in the details of construction, and in the arrangement and combination of parts to be hereinafter more fully set forth and claimed.

In describing the invention in detail, reference will be had to the accompanying drawing forming part of this application, wherein like characters denote corresponding parts in the several views, and in which:

Figure 1 illustrates a plan view of a feeding device embodying the invention;

Figure 2 illustrates a view in end elevation;

Figure 3 illustrates a transverse sectional view;

Figure 4 illustrates a sectional view of a fragment of the trough and parts associated with it on the line 4—4 of Fig. 2.

In the drawing 5 denotes the hollow base, the top of which has an opening 6 which upstanding flanges 7 along two opposed edges of the opening. The interior of the base may have drawers 8 which may be withdrawn from the

base for the purpose of removing accumulations of food which have escaped from the trough and have been directed to the interior of the hollow base. Standards or trough brackets are secured at opposed edges of the base and each standard comprises a length of material bent on itself to form a standard 9, the said material then diverging to form legs or supports 10 and 11, each of which is provided with a foot 12 resting on the upper surface of the base. The feet are held anchored on the base by being engaged by angularly disposed ends 13 of the metal strips 14 that are anchored to the side surfaces of the base by solder, spot welding or the like. It is seen from the foregoing that the standards are firmly secured in place on the base.

The legs 10 and 11 are further engaged by the ends of the flanges 7 which serve to brace the said standards and produce a rigid structure for supporting the trough 15. The trough may be of any appropriate or conventional design and at each end thereof an anchoring bolt 16 extends through said end. A plate 17 at each end with seats such as 18 at its edges embraces or partially embraces the parallel portions of the standard, and said plate is provided with an aperture through which the bolt 16 projects, and a nut 19 of appropriate type is threaded on the bolt and engages the plate to force it into intimate contact with the standard so that the trough is held at different positions of adjustment thereon. As a means for collecting and directing escaping feed, aprons 20 are suspended from the edges of the trough, one on each side thereof and these aprons have hooks 21 on their inner surfaces near the upper edges thereof which hook over and engage the edges of the trough. The aprons are angular and the depending portions thereof extend inwardly under the trough. The aprons converge, as stated, so that those portions of the aprons that are secured to the trough are approximately vertical, whereas the depending portions thereof are at such angle thereto that they project between the flanges 7 and deliver material escaping from the trough to the drawers of the base.

As a description of the operation of the parts has been stated in connection with a description of the parts themselves, a résumé of the operation is believed unnecessary for an understanding of the invention by one skilled in the art.

I claim:

1. In a feed collector, a hollow base having an opening in its top, upstanding flanges on opposed

edges of the opening extending transversely of the base, a trough supported above the opening, and deflecting plates having hangers engaging the edges of the trough for directing escaping feed to the interior of the base, the said deflecting plates extending downwardly between the said flanges.

2. In a feed collector, a hollow base having an opening in its top, a post at opposed edges of the base, a trough, means whereby the trough is adjustably supported on the posts, said posts each comprising a length of metal doubled on itself and having parallel portions, the said metal having diverging portions at the lower ends of the parallel portions forming legs terminating in feet resting on the hollow base, and means attached to the base and overlying the feet for anchoring the posts.

3. In a feed collector, a hollow base having an opening in its top, upwardly extending flanges at opposed edges of the opening, a post at opposed edges of the base, a trough, means whereby the trough is adjustably supported on the posts, said posts each comprising a length of metal doubled on itself and having parallel portions, the said metal having diverging portions at the lower ends of the parallel portions forming legs terminating in feet resting on the hollow base, said diverging portions of the posts engaging the ends of the flanges for stabilizing the structure, and means attached to the base and overlying the feet for anchoring the posts.

ROY LINDQUIST.
